UNITED STATES PATENT OFFICE

2,489,945

AIR INTAKE MEANS FOR CARBURETORS

Antonio G. Abate, Napa, Calif.

Application November 22, 1944, Serial No. 564,588

5 Claims. (Cl. 277—42)

1

My present invention, in its broad aspect, has to do with improvements in carburetor air intake and vaporizer devices, wherein controlling means are provided between a primary and secondary air intake to the end that a more desirable regulation of the amount of air admitted is obtained. My present invention has a movably mounted telescopic funnel, and baffle plates, and inner and outer chambers with a primary air intake tube located in the inner chamber with the conical portion thereof extending through the opening in the bottom of the casing. In connection with my present device, attention is called to my prior Patent #2,029,210 granted January 28, 1936, on Carburetor air intake and vaporizer.

My present device can be applied to conventional types of internal combustion engines without appreciable modification and is designed to improve the character of the explosive mixture. The control rods of my present invention permit the primary air tube and the air adjusting cone to be adjusted upwardly or downwardly to regulate the flow of air, and adjustment of the primary air tube upwardly acts through a rocker arm and push rod to impart corresponding downward movement to the telescopic tube.

Other and equally important objects and advantages of my invention will be apparent from the following description taken in connection with the accompanying drawings, but it is to be understood that changes in form, size, shape, construction and arrangement of parts can be made without departing from the spirit of my invention or the scope of the appended claims.

In the drawings wherein I have illustrated a preferred form of my invention the figure is a vertical section wherein the various operating parts are shown.

In the drawings wherein like characters of reference are used to designate like or similar parts throughout the several views:

The numeral 1 designates the cylindrical outer casing which has an outwardly flared upper portion 2, and a conical bottom wall 3 communicating with a connection 4 to the intake manifold of the engine. Mounted in the casing 1 and spaced from the inner wall thereof is a cylindrical member 9 having an inner chamber 5 and an outer chamber 6 between the member and the wall of the casing. This member is supported by brackets 7. The outer chamber 6 is open at the top and closed at the bottom, and the inner chamber is open at the bottom and closed at the top. Upper downwardly sloping baffles 8 are formed on cylindrical member 9, and inwardly

2

and horizontally extending down baffles 10 are formed on the casing 1 so that air takes a circuitous path. A telescopic cylindrical tube 11 operates between the inner and outer walls 12 and 13 in the member 9. An inner cylinder 15 is provided in chamber 5 in spaced relation to member 9. Cylinder 9 is flanged at its upper end 14 to form with member 9, tube 11 and cylinder 15, a packing gland. Cylinder 15 is flanged at 16 at the bottom to form an abutment for spring 17, the upper end of which bears against the connecting web 18 between tube 11 and an inner tube 19. An air adjusting cone 20 has a flanged top 21 seating on web 18 and bolted as at 22 to the arm 23 of controlling rod 24. Controlling rod 24 has a pin 25 operating in the slot 26 in the support 27 on casing 1. A push rod 28 is threaded as at 29 and extends freely through arm 23 and has an adjusting nut that engages the upper surface of the arm 23. A rocker arm 31 engages the push rod 28 and is pivoted to the standard 32, and has its opposite end connected as at 33 to the web 18 on tube 11.

The lower end of rod 28 is attached as at 34 to the funnel 35 of the primary air intake, so that adjustment of the nut 30 on the rod 28 adjusts both the primary air intake and the secondary air intake represented by tube 11 and chamber 6. Thus the movement of the nut 30 on the rod 28 will cause the arm 23 for the cone 20 to move upwardly according to the position the nut 30 is on the rod 28. Should the rocker arm 31 further move the funnel 35, the arm 23 can move further, should additional air be needed in the operation of the device. In connection with my present invention, it will be further noted that funnel 35 is now adjustable whereas in my prior patent it was fixed.

From the foregoing, it is believed that the operation and advantages of my invention will be apparent, but it is again emphasized that interpretation thereof should only be conclusive when made in the light of the subjoined claims.

I claim:

45. 1. An air intake and vaporizer for carburetors, comprising a plurality of telescoping cylindrical members having their walls interfitting to form inner and outer chambers and constituting a secondary air intake, an air adjusting cone supported by said members, a casing secured to and partially surrounding said members, a funnel-like member engaging the lower portion of the casing and constituting the primary air intake, a spring between the cylindrical members, 50 and a rocker arm mounted on one of said mem-

bers having adjustable connection between the telescoping members and funnel.

2. An air intake and vaporizer for carburetors, comprising a plurality of telescoping tubes or cylindrical members having their walls interfitting to form inner and outer chambers, a funnel-like member adjustably mounted in said inner chamber, a casing enclosing said members on which the funnel-like member is supported, brackets on the casing connected with the telescoping cylindrical members, an adjusting means including a rocker arm mounted on said members whereby adjustment of the funnel adjusts the tubes, a spring acting between the tubes, and a plurality of baffle plates formed on the tubes and casing and extending into the chamber between the tubes and casing.

3. An air intake and vaporizer for carburetors, comprising double walled tubes, reversed and relatively telescoping, packing between the tubes, a spring mounted within and acting on the tubes, a casing partially enclosing and supported by the tubes, a funnel constituting a primary air intake engaging the casing below the tubes, and adjusting means including a controlling rod and a rocker arm connected with the tubes and the funnel to adjust the relative positions of each.

4. The invention as described in claim 3 wherein an air adjusting cone is mounted on said tubes, and wherein the tubes are provided with an upper baffle plate which is downwardly inclined and the casing with lower baffle plate which extends horizontally from a wall of the casing to provide a tortuous path for air entering the device.

5. The invention as described in claim 3 wherein the casing has an outwardly flared flanged top and a conical bottom wall, and a bracket means is attached to the flange of the casing and engages the downwardly inclined baffle on the outer telescoping cylindrical member.

ANTONIO G. ABATE.
